UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,247,468.

Specification of Letters Patent. Patented Nov. 20, 1917.

Application filed May 15, 1917. Serial No. 168,658.

To all whom it may concern:

Be it known that I, GEORGE B. THOMAS, a citizen of the United States of America, and residing at Bridgeport, in the county of Fairfield and State of Connecticut, have invented a certain new and Improved Electric Switch, of which the following is a specification.

My invention relates to electric switches and particularly to push button switches of the three-point type, the object of my invention being to provide a switch of this type of simple and efficient construction which is more economical to manufacture than those of like general type now on the market.

In the accompanying drawings,

Figure 1 is a plan view of a switch in which my invention is embodied in one form;

20 Fig. 2 is a broken side elevation thereof; and

Fig. 3 is a schematic representation of the wiring connections and portions of the switch mechanism.

25 In the embodiment of my invention here shown, the switch comprises a cup-shaped insulating body 10 of generally rectangular shape, having in one corner of the switch chamber a standard 11, carrying switch ter-

30 minal 12 and a binding screw 13 for connecting the wire main from a source of current. At the opposite end of the switch chamber is arranged a second standard 14 with switch terminal 15 and binding screw 16 for connection to one branch line. At the same end of the switch chamber with terminals 11 but on the opposite side there-of is a third standard 17, carrying switch terminal 18 and binding screw 19 for con-

35

40 terminal 18 and binding screw 19 for connection to the second branch line. Arranged centrally in the chamber is a switch

mechanism of generally well-known construction comprising a frame 20 secured to the body 10. In this frame is supported the

45 switch mechanism operated by a pair of push buttons 21, jointed at their lower ends to a rocker bar 22 mounted on the axis 23

Pivoted below the axis of the rocker bar is the switch bar 24 mounted on the spindle 25 and subjected to the action of the usual

coil spring 26. Detent plate 27 engages the switch bar 24 and temporarily restrains the latter against motion in well-known manner during the initial movement of the

rocker 22 so that the switch bar shifts from one position to the other with a snap action. The extent of oscillation of the switch bar 24 is limited by its impingement against the legs of the frame between which it works.

The switch bar 24 comprises a pair of parallel contact blades united by the bridge piece 28 and preferably integral therewith. One of the blades is forked to provide a pair of contact arms 29 and 30 arranged at an acute angle to each other, while the opposite blade comprises a single contact arm 31 having a predetermined relation to the arm 29 of the forked blade. In one position of the switch, the arm 30 makes contact with the switch terminal 12 connected to the line wire, while the arm 29 simultaneously engages the terminal 15 leading to one of the branch circuits, and the blade 31 is in "off" position. In the second position of the switch, the arm 30 of the switch bar is out of contact while the arm 29 now engages the line terminal 12 and establishes connection through the bridge piece 28 with the terminal 18 leading to the second branch circuit.

The switch is primarily designed for house lighting and particularly for upstairs and downstairs hall lights, where it is desired to control either light from the switch. The connection from the terminal 15, for instance, may be led to the downstairs hall light, while the connection from the terminal 18 may be led to the upstairs hall light, through a second switch 31 of like construction. The present switch has the advantage over the construction shown in the co-pending application of C. A. Bates, Serial No. 157,695, that one of the main line switch terminals is eliminated, while the different arrangement of the contact arms 29 and 30 of the switch bar involves less waste of material than that incident to the manufacture of the Bates construction. Furthermore, the switch terminals are all of the same construction and are arranged in like position upon the terminal standard—a further simplification of the manufacturing operations.

I claim as my invention:—

1. A three-point electric switch having a 105 main terminal and two branch terminals in combination with a switch bar comprising a forked contact blade the arms of which

connect alternatively with the main line terminal in the different positions of the switch, while one of said arms connects with one of the branch terminals in one position 5 of the switch and having also a one-armed contact blade electrically connected to said forked blade and arranged to engage the second branch line terminal when the two-armed blade is out of contact with the first 10 mentioned branch line terminal.

2. In a construction such as described in claim 1, the arrangement of the branch line

terminal which co-operates with the forked contact blade of the switch bar on the same level in the switch chamber as the main 15 line terminal.

3. In a construction such as described in claims 1 and 2 the arrangement of the second branch terminal on the same level as the first branch terminal and the main line 20 terminal.

In testimony whereof I have signed my name to this specification.

GEORGE B. THOMAS.
